UNITED STATES PATENT OFFICE.

HENRY CLEMENS, OF MANITOWOC, WISCONSIN.

BOX-OPENER.

1,152,296.

Specification of Letters Patent. Patented Aug. 31, 1915.

Application filed October 30, 1914. Serial No. 869,442.

To all whom it may concern:

Be it known that I, HENRY CLEMENS, a citizen of the United States, residing at Manitowoc, in the county of Manitowoc and State of Wisconsin, have invented new and useful Improvements in Box-Openers, of which the following is a specification.

This invention relates to box openers especially designed for use in connection with such boxes as those containing shoe paste and the like, wherein the cover is held tightly upon the box to prevent evaporation of its contents, and consequently very difficult to remove.

It has been found that in devices of this nature, where a stud carrying the lifting element is journaled in an opening in the body portion of the box, that the stud after being rotated a few times enlarges the opening, thus causing evaporation of the contents of the box, this being essentially true with boxes of the above mentioned character.

It is the object of this invention to overcome the above noted objections by mounting the stud in fixed relation to the box in such manner that the opening therein will be closed, and having the cover lifting element rotatably mounted thereon.

Among other features which will appear, the invention resides in the specific construction, combination and arrangement of parts hereinafter more fully described.

In the drawing forming a part of this application like numerals of reference indicate similar parts in the several views and in which:

Figure 1 is a perspective view of the box with my device applied. Fig. 2 is a view of the box with the cover partly removed showing the manner of using the device. Fig. 3 is a plan view with the cover removed. Fig. 4 is a detail view of the pivot stud and key.

Referring to the drawing in detail 5 designates the body portion of a box having an annular bead 6, the cover being indicated at 7 having a flared marginal edge portion 8 for engagement with the bead 6 when in position on the box. The bead 6 and the flared portion 8 of the cover are cut away as at 9 to permit the device forming the subject matter of my invention to be operatively associated beneath the marginal edge portion of the cover.

The device comprises a pivot stud 10 which projects from the side of the box 5

at a point immediately above the cut away portion 9 of the bead 6, and upon the latter is mounted for rotation a key 11. The stud is provided with a reduced end portion 12 extended through a suitable opening in the side of the box 5 and upturned against the inner face thereof with a view of closing the opening. The reduced portion 12 defines a shoulder 13 which engages the outer surface of the box, and between which and the flattened extremity of the stud, the latter is mounted upon the box in fixed relation thereto. By reason of this construction and arrangement it will be noted that the opening in the box through which the stud 10 extends, is at all times effectively closed thereby preventing evaporation of the contents of the box.

Mounted for rotation upon the pivot stud 10 is a cover lifting element 14, in the nature of a key constructed from a substantially elongated piece of metal slit longitudinally through the center at spaced points 16, the strips 17 formed by the slits being alternately bent in opposite directions to form bearings for the reception of the stud 10, the latter being headed as at 18 for engagement with the outer edge of the key to prevent casual separation of the members. Projecting centrally from the inner edge of the finger portion of the key and arranged at opposite sides of the stud are lugs 19 which underlie the marginal edge of the cover, and adapted to force the latter upwardly from the box upon rotation of the key. The device is extremely simple in construction and while I have shown and described the same as being primarily intended for use in conjunction with blackening boxes, I desire to have it understood that it is susceptible for use with boxes of different contours and dimensions.

It is believed that from the foregoing description the nature and advantages of the invention will be readily understood without requiring a more extended explanation and therefore the same has been omitted.

What I claim is:

The combination with a box and cover therefor, said box having an opening in the side thereof, of a headed stud having a reduced end portion extending within said opening and having its extremity flattened against the inner surface of the box, said reduced end forming a shoulder engaging the outer surface of the box and closing said

opening, a key mounted for rotation upon the stud and comprising an elongated body having oppositely disposed bulged portions loosely embracing said stud, and lugs projecting from the inner edge of said body in parallelism with the stud and terminating in a line with said shoulder thereof.

In testimony whereof I affix my signature in presence of two witnesses.

HENRY CLEMENS.

Witnesses:

WENZEL J. HOUFEK,
FRANK J. JANSKY.
